UNITED STATES PATENT OFFICE.

JOHN A. KNISELY AND WILLIAM J. KLEMM, OF CHICAGO, ILLINOIS; SAID KLEMM ASSIGNOR TO SAID KNISELY.

FIREPROOF METAL WINDOW.

SPECIFICATION forming part of Letters Patent No. 743,088, dated November 3, 1903.

Application filed February 12, 1903. Serial No. 143,156. (No model.)

To all whom it may concern:

Be it known that we, JOHN A. KNISELY and WILLIAM J. KLEMM, citizens of the United States, residing at Chicago, in the county of 5 Cook and State of Illinois, have invented certain new and useful Improvements in Fire-proof Metal Windows, of which the following is a specification.

Our invention in this instance relates to 10 improvements in the construction of fire-proof metal window frames and sash of that type in which the parts or members are in hollow or box-like forms built up of sheet-metal plates or strips of copper or galvanized 15 iron pressed into suitable shapes to produce the sills, stiles, heads, and rails which are secured together by interlocking flanges, rivets, and solder and arranged to produce more or less weather-tight and dust-proof windows.

20 The particular improvements which we wish to embody in this application have reference to the formation of the sash and co-operating frame, the relative arrangement of said parts in both stationary and swinging 25 types of windows, and to the manner of securing the glass in the sash.

The especial objects of our improvements are economy in construction both as to material and labor, the avoidance of the use of 30 solder to produce tight joints which will be dust and weather proof and to give a neat and smooth finish by making the joints without external or visible seams, to permit the parts to be made by machinery, so that they 35 may be quickly assembled with but little hand labor, and to effect tight joints at the sides, the top, and bottom of the swinging sash when it is closed against its frame.

Subordinate objects and advantages resulting from improved methods of construction 40 will clearly appear from the details herein-after set forth.

In the accompanying drawings, which form a part of this application, we have shown our 45 improvements in preferred form in the following views.

Figure 1 is a vertical section taken near the center line of a combination-window embodying our invention. Fig. 2 is a vertical 50 section, on an enlarged scale, taken through a window-frame sill and head and the top

and bottom rails of a swinging sash. Fig. 3 is a transverse section through one stile and the mullion of the swinging sash and one side or jamb of the frame at a point above 55 the pivot-hinge. Fig. 4 is a view similar to Fig. 3, but taken at a point below the pivot-hinge. Fig. 5 is a cross-section through one stile and one side of the frame or jamb of the stationary portion of the window. Fig. 60 6 is a fragmentary detail in perspective of the body portion of the sash-stile. Fig. 7 is a detail in perspective of the overhanging or double flange which is attached to the stile of the swinging sash and extends from the 65 pivot to the top of the sash. Fig. 8 is a detail in perspective of the straight flange or tongue which forms a part of the jamb and extends from the pivot-point to the head of the frame, and Fig. 9 is a detail showing a 70 fragment of the jamb alone.

For convenience we will describe, first, the construction of the window-frame, then the sash, and, lastly, the parts as assembled and coöperating to form a complete window. 75

By the term "combination - window" we mean that form in which a stationary or fixed sash occupies the lower half, and a horizontally - swinging sash the upper half, of the frame. 80

The frame for a combination - window is built up of a sill A, jambs F, center cross-rail B, and head or lintel C, and the sill and head are joined to the jambs in any suitable and well-known manner. In all of said parts 85 the sheet metal is bent longitudinally to provide in cross-section the hollow or box-like forms common to such constructions, and same will not be particularly referred to in the specific description of said parts herein-after given. When the entire frame is occupied by a swinging sash alone, the rail B becomes the sill of the frame. The jambs F are made up of two strips or plates of sheet metal, which are longitudinally bent to produce the rectangular (in cross-section) forms shown in Figs. 5 and 9, and the respective edges of these strips are bent to form outwardly-turned flanges f' and inwardly-turned flanges f'' , the former being adapted to receive other flanges on parts to be described and the latter to receive any suitable closure 95 100

for the rear side of the frame, which forms no part of this invention and is therefore not shown. As these flanges extend throughout the length of the jambs, they run from 5 sill to lintel or head of the frame.

The sill A is formed from a single strip of metal bent longitudinally to provide a groove or socket a^1 to receive the lower edge of the glass G and bent upon itself to form a vertical rib a^2 , which bears against the inner edge of the glass, holds it securely along the bottom, and serves to exclude dirt, &c.

The rail B, which serves as a sill for the swinging sash and as a head for the fixed 15 sash, is constructed from a single strip of metal bent to form an inclined meeting face b^3 and a shoulder b^4 on its weather side and doubled upon itself to form the flange b' , between which and the face b^3 a channel b^6 is 20 provided. In this channel or recess a weather-strip b^5 may be secured in any preferred manner to assist in effecting a specially tight closure with the swinging sash, as indicated in Fig. 2. In the under side of the rail an opening b^4 is left between the edges of the strip, into which the upper edge of the glass of the permanent sash is inserted and which permits the glass to be pushed upwardly, so as to clear the rib or flange a^2 along the sill 25 when the glass is being placed in position in the sash.

The head or lintel C is formed from a single piece or strip of metal bent to the form shown in cross-section in Fig. 2, and along the rear 30 lower corner the metal is doubled upon itself and then bent to form an inwardly-turned horizontal flange c' , between which and the lower inclined face c^4 is a longitudinal recess or socket c^5 , which is adapted to receive a portion 35 of the swinging sash when the latter is closed, as will be hereinafter described. In this recess a weather-strip c^2 of suitable material may be placed if a specially tight window is desired. The lower side of the lintel is also 40 bent longitudinally to form a vertical shoulder c^6 , against which a portion of the sash strikes and rests when the latter is closed.

The stationary sash is made up of the sill A, rail B, and two stiles H, between which 45 extends the usual mullion M to receive and hold the inner edges of the panes of glass, it being presupposed that two panes are used to the sash. The stiles are each formed from a single strip of metal bent to provide the 50 groove for the pane of glass G and having its edges bent inwardly, as at h' , to form the flanges, which are adapted to interlock with the flanges f' on the jambs. These stiles are placed in position in the frame by sliding the 55 flanges h' into the flanges f' from above before the rail B is fixed in its position, and the interlocked flanges are then pressed or hammered to make them fit tight, as indicated in Fig. 5. The mullion M forms no part of 60 this invention.

The swinging sash is composed of a top rail D, bottom rail E, and stiles J K, with the

mullion M, all of which are joined together in any suitable manner. The top rail is formed from a single strip of metal bent longitudinally to form the usual socket d' for the glass and doubled upon itself to form along its upper rear corner the interlocking flanges d^3 , which when the sash is closed project into the recess c^5 of the lintel and contact with the weather-strip c^2 therein located, or, if no weather-strip be used, against the rear wall of such recess. Said strip is also doubled upon itself and the two thicknesses bent to form the upwardly-extending vertical flange d^4 , which parallels and strikes against the shoulder c^6 of the lintel when the sash is closed. The socket d' is made sufficiently deep to permit the pane of glass to be pushed upwardly therein, so as to clear the walls of the socket in the upper side of the rail E, when it may drop into said socket. To prevent the glass from being pushed up out of the lower socket after the window is finished, we place over the upper edge of the glass before inserting it in the socket d' several small clips of bendable metal, as d^2 , and when the pane is in place bend up the exposed ends of the clips, as shown in Fig. 2, and, if desired, these ends may be soldered to the portions of the rail, which they engage.

The lower rail E is composed of a single strip of metal, which is bent or doubled upon itself to form the inwardly-extending flange or tongue e^2 , which projects into the recess b^6 of the frame-rail B and strikes either against the rear wall of said recess or against the weather-strip b^5 , secured to such wall, as indicated in Fig. 2. The bottom of the rail E inclines downwardly toward the weather side of the sash, as at e^3 , thus lying parallel with the upper face of the rail B, and the edges of the strip are bent to form the interlocked vertical flange e' , which strikes against and lies parallel with the shoulder b^3 of the said rail B when the sash is closed.

From the foregoing description of the top and bottom rails and of the parts B and C of the frame it will be seen that each of said rails has three points of contact with the adjacent parts of the lintel and sill or rail B, at one of which a weather-strip may be applied, if desired. It should also be noticed here that the coating flanges and recess-walls are integrally formed with their respective parts of frame or sash.

The portion of the swinging sash-stiles below the pivot-hinge point we have designated as J and the part above such point as K in order to clearly distinguish them apart in the description, though it should be understood that they are continuous and integral structures in the main. The part J is formed by bending the metal strip longitudinally to provide the usual socket for the glass, and its edges are respectively bent to form (in cross-section) a vertical flange j^5 and a horizontal flange j^4 . A separate strip of metal is bent upon itself to form a tongue j' , and its edges

are doubled to form flanges $j^2 j^3$, which are adapted to receive the flanges $j^5 j^4$, respectively, of the stile-strip, thus securing the tongue to the stile, so that it extends inwardly and at right angles with the face of the latter. When the sash is closed, this tongue projects into the recess between the walls of the overhanging flange f^6 , the latter forming a meeting-strip for said tongue. The flange f^6 is formed by bending a strip of metal longitudinally upon itself and then bending the doubled metal upon itself to the form shown in Fig. 4, and the edges of the strip are bent at right angles to provide the flanges $f^3 f^4$, which interlock with the corresponding flanges f' of the jamb F. Above the pivotal point, which is the location of the pin of the hinge M', the stile K is made in the same manner as it is below said point; but in lieu of the tongue j' it is fitted with the double flange k' , which is of the same form as the flange f^6 and extends inwardly from the face of the stile. This flange k' is formed from the same strip that makes the tongue j' , the metal being cut sufficiently wide to allow for the extra material required to produce such form, and the edges are bent to produce the flanges $k^2 k^3$, which are continuations of the flanges $k^2 k^3$ of the tongue-strip and have the same function of interlocking with the flanges $k^4 k^5$ of the stile, the latter also corresponding with the flanges $j^4 j^5$ of the stile-section J.

Above the pivotal point of the sash the jambs are supplied with a tongue f^2 , which is formed in substantially the same manner as the tongue j' on the sash-stile and projects between the walls of the double flange k' when the sash is closed. The edges of the tongue-strip are bent upon themselves to form the flanges $f^3 f^4$, which interlock with the flanges f' along the edges of the adjacent portion of the jambs, thus securing the tongue to the latter in the same manner that the double flange f^6 is secured to the jamb below the pivot-point.

From the construction above set forth it will be seen that above the hinge-pivot the sash-stiles are provided with the double flanges k^6 , which overhang the tongues f^2 along the corresponding portion of the jambs, while below said pivot the sash-stiles are provided with tongues j' , which project into and are overhung by the double flanges f^6 along the corresponding portions of the jambs when the window-sash is closed against the frame. It will also be apparent that as the ends of these tongues and flanges contact with each other or with some portion of the stiles or jambs at two points throughout their length an effective provision is made for the exclusion of the elements. The construction set forth permits the stiles and jambs to be pressed into their respective shapes by suitable dies and presses and the tongues and double flanges to be formed in the same manner and that when said parts are assembled it is only necessary to slide their coöperating

or interlocking flanges together from the ends of the parts, and the operation is completed by pressing the interlocked flanges tightly together.

In Fig. 1 we have shown our improvements in a complete window embodying a lock or latch L, a pivot-hinge M', and a latch-tripping device N; but these form no part of the invention embraced in this application and are therefore not particularly described herein.

What we do claim, and desire to obtain by Letters Patent in this connection, is—

1. In a metal window, a frame-jamb formed from strips of sheet metal having their edges bent to form flanges f' , and a sash-stile formed from a single strip of metal bent to form a socket for the glass, and having its edges bent to provide flanges adapted to interlock with the flanges on the jamb.

2. In a sheet-metal window, a frame-jamb formed from two strips of metal having their edges bent to form flanges f' , a third strip bent to form a tongue extending parallel with the face of the jamb and having its edges bent to form flanges adapted to interlock with the flanges on the jamb.

3. In a sheet-metal window, a frame-jamb formed from two strips of metal having their edges bent to form flanges f' , a third strip bent to form a double flange extending parallel to the face of the jamb, the edges of said strip adapted to interlock with the edges of the jamb.

4. In a sheet-metal window, a frame-jamb composed of two strips of metal having their edges bent to form flanges f' , and a third strip of metal bent upon itself to form for a portion of its length, a double flange f^6 , and having its edges adapted to interlock with the edges of the jamb.

5. In a sheet-metal window, a frame-jamb composed of two strips of metal having their edges bent to form flanges f' , and a third strip bent upon itself to form, for a portion of its length, a tongue f^2 , and for the rest of its length, a double flange f^6 , and having its edges bent to provide flanges adapted to interlock with like flanges on the jambs, in combination with a sash-stile composed of a single strip of metal having inturned flanges along its edges, and provided with a tongue for a portion of its length, and with a double flange for the rest of its length, said tongue and double flange adapted to coöperate with like portions on the jamb in the manner described.

6. In a metal window, a frame having suitable jambs, and a head or lintel composed of a single strip of metal bent to form a flange c' and a shoulder c^6 .

7. In a metal window, a frame having suitable jambs, and a rail composed of a single strip of metal bent to form a flange b' and a shoulder b^6 .

8. In a metal window, a frame provided with a lintel composed of a single strip of metal bent to form a flange c' and a shoulder c^6 ,

also provided with a sill composed of a single strip of metal bent to form a socket for the glass and to form a retaining-rib a^2 , in combination with a rail composed of a single strip 5 of metal bent to form a flange b' and a shoulder b^8 .

9. In a metal window, a swinging sash having its stiles each constructed from a strip of metal bent to form a socket for the glass and 10 having its edges bent inwardly to form flanges, and a supplemental strip bent upon itself to form a tongue j' and a double flange k' , and having its edges adapted to interlock with the flanges on the stile proper.

15 10. In a metal window, a swinging sash having its top rail constructed from a strip of metal bent to form the glass-socket d' , and also bent upon itself to form the flanges d^8 and d^4 .

20 11. In a metal window, a swinging sash composed of a top rail constructed from a strip of metal bent to form a socket for the glass,

and bent upon itself to form the flanges d^3 , d^4 , of a bottom rail constructed from a strip of metal bent to provide a socket for the glass, and bent upon itself to form flanges e' , 25 e^2 , and of stiles each constructed from a strip of metal bent to provide a socket for the glass, and having its edges bent inwardly to form flanges, and a supplemental strip of metal bent longitudinally for a portion of its length to form the double flange k' , and for 30 the rest of its length to form the tongue j' , the edges of said strip adapted to interlock with the flanges on the edges of the stile.

In testimony whereof we affix our signatures in presence of two witnesses.

JOHN A. KNISELY.
WILLIAM J. KLEMM.
